UNITED STATES PATENT OFFICE.

CHARLES H. MUCKENHIRN, OF DETROIT, MICHIGAN.

DESIGN FOR A REAR-LAMP LENS.

Application filed July 9, 1923. Serial No. 6,735. Term of patent 7 years.

To all whom it may concern:

Be it known that I, CHARLES H. MUCKENHIRN, a citizen of the United States, residing at Detroit, in the county of Wayne and State of Michigan, have invented a new, useful, original, and ornamental Design for Rear-Lamp Lens, of which the following is a specification, reference being had to the accompanying drawings, forming a part hereof.

The figure is an elevation of a combined stop and tail light plate constructed in accordance with my invention.

I wish it understood that the word, "Maxwell" appearing across the face of the design may be replaced with any other suitable name according to the desires of the maker and to accommodate different makes of automobiles.

I claim:

The ornamental design of a rear lamp lens as shown.

CHARLES H. MUCKENHIRN.
